UNITED STATES PATENT OFFICE.

WILLIAM J. McNORTON, OF ALLEGHENY, PENNSYLVANIA.

INCANDESCENT GAS-BURNER.

SPECIFICATION forming part of Letters Patent No. 389,588, dated September 18, 1888.

Application filed January 20, 1888. Serial No. 261,375. (No model.)

To all whom it may concern:

Be it known that I, WILLIAM J. McNORTON, of Allegheny, in the county of Allegheny and State of Pennsylvania, have invented certain new and useful Improvements in Incandescent Gas-Burners; and I do hereby declare the following to be a full, clear, and exact description of the invention, such as will enable others skilled in the art to which it pertains to make and use it, reference being had to the accompanying drawings, which form part of this specification.

My invention relates to an improvement in incandescent gas-burners.

15 The object of my invention is to produce a burner which is adapted both for natural and artificial gas, and in which the size of the flame can be regulated to the amount of light desired, and to which filaments of any indestructible nature are applied, so that the flame will heat the filaments white-hot, and thus cause them to produce a brilliant and steady light by the consumption of a very small amount of gas.

25 Figure 1 is a vertical section of a burner which embodies my invention. Fig. 2 is a side elevation of the same.

A represents the tip through which the gas escapes, and B the perforated cylinder into the 30 lower portion of which the gas escapes, as in an ordinary Bunsen burner. The upward flow of the gas causes air to be introduced through the openings C in the bottom of the cylinder and to mingle with the gas for the purpose of producing an invisible heating-flame. This 35 flame produces no light, but does produce an intense heat for the purpose of heating the filaments.

The cylinder B is internally screw-threaded 40 at its upper end for any suitable distance, and placed inside of this screw-threaded cylinder is a plug or support, D, which is cut away upon its sides and perforated at its ends, as shown, so as to allow the gas to freely escape upward 45 past it, and which plug serves as a support for the other portions of the burner. Rising from the top of this plug D is a screw-threaded rod, E, and placed down over this rod and in connection with the top of the plug is the inverted 50 cone H, which is clamped in position by means

of a sleeve or collar, I, which is screwed upon the rod, as shown in Fig. 1. This cone serves to regulate the size of the opening at the top of the cylinder B, and thus regulate the size of the flame. When the plug is screwed downward inside of the cylinder, the sides of the cone are brought always in contact with the upper inner edges of the cylinder, and the flame will be adjusted accordingly; but when the plug is raised upward the aperture for the escape of the gas is accordingly enlarged, and the flame is increased in size accordingly. Placed upon the screw-rod and made vertically adjustable thereon is the plate or disk J, which is made separate and independent of the cone, 65 as it must be adjusted either up or down upon the rod at the same time that the cone and plug are adjusted in relation to the top of the cylinder. Upon the outer edge of this disk is placed a supporting-ring, O, which is made 70 independent of the disk and to which the filaments P are secured. These filaments are of any desired number, length, and thickness and made of any suitable indestructible material—such as platinum, iridium, or zirconia. These 75 filaments become white-hot by the flame and produce a brilliant and steady light. The filaments are comparatively short and require to be accurately adjusted in relation to the flame, and hence the supporting plate or disk 80 is made vertically adjustable upon the screw-rod, so that whenever the size of the flame is changed or adjusted the filaments can be adjusted at the same time.

By means of the construction here shown 85 and described about three times the amount of light can be produced from the same consumption of gas as by a burner of the ordinary construction. For about every foot and a half of natural gas and every two feet of artificial gas 90 a sixteen-candle-power light can be produced, which is more steady, more brilliant, and which will produce at least three times as much light as an ordinary gas-burner. The filaments may be constructed or woven as is here 95 shown, or in any other way that may be preferred, and the meshes must be proportioned to the size of the flame desired. This filament being heated to a white heat by the flame produces a brilliant and steady light.

As above stated, the flame from the burning gas is invisible, and the whole light is produced by heating the filament to a white heat. The flame passes both inside and outside of the filaments as it escapes from the top of the cylinder, and the filaments must be made adjustable in relation to the flame according to the size of the flame desired, so as to prevent those explosions which extinguish the light.

10 If the parts are not adjusted just right, small explosions occur and extinguish the flame.

Having thus described my invention, I claim—

1. The combination, with a Bunsen burner, 15 of a vertically-adjustable plug or support connected thereto, a screw-rod which projects above the cylinder of said burner, a cone for regulating the size of the flame, a supporting plate or disk, and filaments of suitable incandescent material which extend downward outside of the cone, substantially as shown.

2. The combination, with a Bunsen burner, of a vertically-adjustable plug or support which is placed inside of the perforated cylinder of said burner, a screw-rod which projects upward from the plug, a cone which is secured to the rod and plug, a vertically-adjustable supporting-plate which is made independent of the cone, and incandescent filaments which are supported by the plate or disk, substantially as shown. 25

3. The combination, with a Bunsen burner, of a cone and an adjustable incandescent mantle which conforms to the shape of the cone, substantially as set forth. 30

In testimony whereof I affix my signature in presence of two witnesses:

WM. J. McNORTON.
